UNITED STATES PATENT OFFICE.

JESSE C. JOHNSON, OF DELRAY, FLORIDA.

HYDROCYCLE.

Application filed November 14, 1925. Serial No. 69,091.

The object of this invention is to provide a device which may be used by life guards and swimmers, and may also be used purely for amusement, the device including an air tank suitably proportioned for supporting a rider on a saddle carried by the tank, and including driving mechanism and guiding means.

A further object is to provide a device of this kind with horizontal and vertical rudders, permitting of lateral and vertical control, or depth control, and driving mechanism including a propeller and a shaft and gearing to be driven by cranks and pedals, as in the case of a bicycle.

With the foregoing and other objects in view, the invention consists in the novel construction and arrangement of element described, illustrated and claimed, it being understood that modifications may be made within the scope of the claims without departing from the spirit of the invention.

In the drawings forming part of this application,

Figure 1 shows the device in longitudinal section.

Figure 2 is a vertical transverse section on line 2—2 of Figure 1.

Figure 3 is a section through the housing for the gearing, between the pedal cranks and the propeller shaft.

In carrying out the invention, I employ an air tank 10 having tapered end portions 11 and 12 and being proportioned to support a rider, a saddle 13 being provided for this purpose.

The driving mechanism is suspended below the tank by means of straps or the like shown at 14, 15, 16, 17 and 18. These straps 40 or a portion of them include, or have connected therewith extension straps 15', 16' and 17', some of the extensions having direct connection with the gear housing as shown in Figure 2, where the housing is designated 20.

The extension straps or elements 17' have connection with a bearing 22 for propeller shaft 23, this shaft also passing through bearings 24 in the wall of the housing 25 for the gearing. A lower horizontal brace or tie member is shown at 26, and other braces are illustrated at 27 and 28, the pur-

pose being obvious and the connection being readily understood.

A rudder 30 includes a vertical blade, and 55 a rudder post 31 adapted to be operated by the arm or handle portion 32, post 31 extending through tube 33 which has airtight connection at the end with the walls of the tank 10, so that there will be no leakage of 60 air or water in connection with the mounting of the rudder. A suitable filling connection for tank 10 will of course be provided.

Another rudder includes blade 35 mounted 65 in the manner shown, the axial element being designated 36, and the blade being normally horizontal when the device is to be maintained on a given level.

The blade or rudder 35 is controlled by a 70 rod 36 and lever 37 pivoted at 38. A tube 39 serves a purpose similar to that of the tube 33.

The propeller 40 carried by the shaft 23 is driven by a gearing similar to that of a 75 standard type of bicycle, the gearing including pinion 41, gear wheels 42 and a transverse shaft 43. The pedals, or the cranks therefor are designated 44 and 45, in Figure 3, and the pedals per se are shown in 80 the other views and are there designated 46.

The operation of the device will be fully understood without further description, and it is clear that the tank may be of such a size, or of different sizes, in different machines or devices, to permit of carrying one or more passengers.

What is claimed is:—

1. In a device of the character described, an air tank, tubular members extending 90 therethrough and open exteriorly thereof, shafts extending through the tubular members, vertical and horizontal blades, controlled respectively by the shafts and mounted below the tank, a propeller, and 95 means for imparting motion to the propeller.

2. In a device of the character described, an air tank, tubular members extending 100 therethrough and open exteriorly thereof, shafts extending through the tubular members, vertical and horizontal blades controlled respectively by the shafts and mounted below the tank, a propeller, and

foot power operated means for driving the propeller.

3. In a device of the character described, an air tank, a saddle carried thereby, a propeller, driving means for the propeller, straps surrounding the tank and extending below the latter for suspending the driving means and propeller below the tank, rudders

mounted below the tank, tubular elements extending through the tank and open at their upper and lower ends, exteriorly of the tank, shafts extending through the tubular elements, and means for controlling the shafts and rudders.

In testimony whereof I affix my signature.
JESSE C. JOHNSON.
